UNITED STATES PATENT OFFICE.

INGOLF BIRKELAND, OF FORT BENTON, MONTANA.

SHOCKING-MACHINE.

1,357,269.

Specification of Letters Patent.

Patented Nov. 2, 1920.

Application filed October 14, 1918. Serial No. 257,968.

To all whom it may concern:

Be it known that I, INGOLF BIRKELAND, a citizen of the United States, residing at Fort Benton, in the county of Chouteau and State of Montana, have invented a new and useful Shocking-Machine, of which the following is a specification.

This invention relates to shocking machines.

One of the objects of the invention is to provide a light; durable and inexpensive machine, eliminating gearings, cranks, push rods and like devices which have been used in machines of this character heretofore devised, and which is adapted to be coupled to and actuated by any form of grain binder.

A still further object is to provide a machine which will gather the bundles delivered from a binder, form them into a shock, firmly compress the shock and deposit it on the ground with its base spread so that the shock will stand.

Another object is to provide a machine of this character under constant control of the operator seated on the binder, there being means whereby the operator can control the time of depositing the shocks, whereby the shocks may be set in windrows, all other operations being automatic.

Another object is to provide a machine which will hold any bundles delivered from the binder pending the formation and depositing of these shocks.

Another object is to provide a shocking machine having a shock former the sides of which constitute shock compressing means, the base of the shock former operating to spread the butt end of the shock prior to depositing the same on the ground, the extent to which the base of the shock is spread depending solely upon the length of the shock and not upon the number of bundles constituting the shock.

Another object is to provide simple and efficient means for keeping the bundles parallel as they are being deposited in the shock former, this means nevertheless permitting the bundles to spread out against the sides of the shock former so as not to reduce the capacity of the shock former, means being employed for keeping the butts of the bun-

dles out of contact with the supporting and spreading devices until after the shock is formed and ready to be deposited on the ground.

A further object is to provide a shock former in which the supporting means is adapted to be lowered to and lie upon the ground and subsequently to slip out from under the shock, means being employed whereby the shock compressing sides of the former are instantaneously released when the shock is deposited on the ground, thereby to permit the free withdrawal of the shock former from the deposited shock without danger of pulling the shock over on its side.

With the foregoing and other objects in view, which will appear as the description proceeds the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—

Figure 1 is a front elevation of a shocking machine embodying the present improvements, the shock former being shown elevated to bundle receiving position, some of the parts of the machine being broken away.

Fig. 2 is a plan view of the structure with the parts in the position shown in Fig. 1, certain portions of the device being broken away.

Fig. 3 is an elevation of the outer side of the machine, the parts being arranged as in Figs. 1 and 2 and the flexible front apron being shown in section, the lever stop being shown in section.

Fig. 4 is a view partly in plan and partly in section taken approximately on line 4—4 Fig. 3, said view being on an enlarged scale.

Fig. 5 is a section on line 5—5 Fig. 4.

Fig. 6 is a side elevation of certain of the locking levers shown in Fig. 4.

Fig. 7 is a plan view of the machine showing the shock former moved to delivering position.

Fig. 8 is an elevation of the outer side of the machine with the parts in the positions shown in Fig. 7, the lever stop being shown in section.

5 Fig. 9 is a view showing diagrammatically a cross section through the shock former in bundle receiving position and the arrangement of the centering cables for holding the bundles parallel.

10 Fig. 10 is a section through one of the winding drums.

Referring to the figures by characters of reference A designates a portion of the frame of a binder and secured to and extending outwardly and upwardly from this portion of the frame are front and rear bars 1 and 2 merging into vertical members 3 and 4 respectively which, in turn, are provided at their upper ends, with horizontal portions 5 and 6. These bars with their upwardly and horizontally extended portions constitute the upstanding frame of the machine forming the present invention and the said bars may be connected wherever desired by cross members thus to form a rigid structure. The front horizontal portion 5 has its free end curved rearwardly as indicated at 5^a while the rear horizontal portion 6 is shorter than the portion 5 as shown particularly in Figs. 2 and 7.

The frame made up of the bars 1 and 2 may be suitably connected to the binder by braces 7 and which braces are preferably attached to the bars 1 and 2 close to the upstanding portions 3 and 4. The pitman drive shaft B of the binder is arranged along the portion A of the frame and supported above the shaft and said portion A is the deck C of the binder extending under the shaft D of a kicker arm E of a binder.

40 Bearings 8 are attached to the upstanding portions 3 and 4 of the frame members and journaled in these bearings is a transverse shaft 9 to which are keyed sprockets 10. One end of this shaft projects beyond the frame member 1 and is journaled in a bracket 11 secured to the upstanding portion 3 of said member. Loosely mounted on this projecting portion of the shaft 9 is a gear 12 formed with or secured to a sprocket 13, this sprocket being provided with a clutch member 14. A chain 15 is adapted to transmit motion to the sprocket 13 from a small sprocket 16 secured to the pitman drive shaft B.

Engaging the sprockets 10 are elevator chains 17 having outstanding fingers 18, these chains being extended vertically from the sprockets 10 upwardly to sprockets 19 mounted on the upper ends of the vertical portions 3 and 4 and being then extended laterally to sprockets 20 secured to a transverse shaft 21 mounted on the horizontal portions 5 and 6. Said chains are then extended over sprockets 22 arranged under the

horizontal portions 5 and 6 and thence downwardly to the sprockets 10. Thus it will be seen that the fingers 18 will be brought successively to position beyond the vertical portions 3 and 4 so that they will move upwardly to the upper ends of said portion and then horizontally until they reach the sprockets 20 whereupon the fingers will move back to their initial positions, passing between the sprockets 22.

75 A sheet metal plate 23 is secured to the vertical portions 3 and 4 of the frame members and extends from the upper ends thereof downwardly to a point above the shaft 9 where the plate is curved downwardly and outwardly to form a trough 24, the lower end of the plate 23 being fastened to and under the deck C of the binder. This plate 23 is slotted longitudinally as indicated at 25 to permit the fingers 18 to travel vertically between the sprockets 10 and 19.

Guide rods 26 extend from the shaft D and upwardly parallel with the vertical portions 3 and 4 of the frame members, the upper ends of these rods being bowed over the space between the frame members, as shown at 27 and having their free ends projecting downwardly into said space. Thus it will be seen that any bundles discharged from the binder deck C will be deposited in the 95 trough 24 and there be engaged by the kicker arms E which will direct them into the paths of the fingers 18. These fingers, which are moved upwardly with the chains 17 when the shaft 9 is rotated, will convey 100 the bundles upwardly between the plate 23 and the guide rods 26 and carry said bundles over the sprockets 19 and 20 and deliver them into the space between the frame members 1 and 2.

105 A sheet metal plate 28 is secured to the upstanding portion 3 and the horizontal portion 5 of the front frame member 1 but the side portion of this plate 28 is disconnected from the curved portion 5^a of the 110 frame member so that said side portion is free to flex toward or from said curved portion as shown particularly in Figs. 2 and 7.

Journaled within the upstanding portions 3 and 4 of the frame members 1 and 2 and above and parallel with the shaft 9, is a shaft 29 one end portion of which projects forwardly and is journaled in the bracket 11. Loosely mounted on this shaft 29 and close to the upstanding portion 3 is a drum 120 30 and arranged at one end of the drum is a ratchet wheel 31 which is keyed to the shaft. A pawl 32 is pivotally connected to the upstanding portion 3 and normally engages the ratchet wheel 31 to hold it against 125 rotation in one direction. Arranged within the drum 30 is a coiled spring 33 and one end of this spring is secured to the drum 30 while the other end is secured to the ratchet wheel 31. Thus it will be seen that when 130

the drum 30 is rotated in one direction while the ratchet wheel 31 is being held against rotation, the coiled spring 33 will be placed under increased tension.

5 Loosely mounted on the shaft 29 is a gear 34 which constantly meshes with the gear 12 and has a clutch member 35. Secured on the shaft 29 is a clutch member 36 and another clutch member 37 is severed on the 10 shaft 9. These two clutch members are mounted for rotation within the end portions of a lever 38 and springs 39 and 40 are mounted on the shafts 29 and 9 respectively and bear at their forward ends 15 against the bracket 11 and at their other ends against the lever 38. A stop 41 is engaged by the lever 38 at a point above the center thereof, said lever being pressed against the stop by the two springs 39 and 20 40. A latch lever 42 is pivotally connected to the lower portion of the bracket 11 and is adapted, when the lower end of the lever 38 is pulled away from chain 15, to engage said lower end and thus hold the lever 25 against the action of spring 40 while, at the same time, the clutch member 36 will be shifted into engagement with the clutch member 35 under the action of the spring 39, which presses the lever against stop 41 30 which thus constitutes a fulcrum.

A lever 43 is mounted on the bracket 11 and one arm of this lever is connected by a rod 44 to an intermediate portion of the lever 38. The other arm of lever 43 is connected by a cable 45 to an actuating cable 46 which is connected to the pawl 32 and is adapted to be operated by the occupant of the binder. In other words when this cable 46 is pulled by the operator, the pawl 32 will 40 be disengaged from ratchet wheel 31 and lever 43 will be shifted so as to pull the lever 38 out of its normal position.

Pivotally connected to the portion A of the binder frame at 47 is a laterally extending tilttable frame 47 extending under the space between the frame members 1 and 2 and preferably substantially triangular in outline, the outer or free end of this tilttable frame being formed with a bearing plate 50. A pivot bolt 49 is extended through the bearing plate and engages a turn table 50 one end of which is semicircular and has an upstanding semicircular flange 51 provided, in its outer face, with a groove 52. Parallel 55 upstanding side flanges 53 are formed on the turn table and they constitute bearings for a cross rod 54. Journaled on the turn table with its periphery flush with one end of the grooved flange 51 is a pulley 55 and 60 journaled between brackets 56 on the turn table and close to the semicircular end of said turn table is a pulley 57 mounted to rotate about a substantially horizontal axis disposed at right angles to the side flanges 53. 65 Tiltably mounted on the pivot rod 54 are

the sides of a tilttable frame 58, these sides normally resting on the turn table 50 and extending some distance beyond the semicircular end of the turn table. The free ends of the side members 58 are provided 70 with upstanding arms 59 at right angles thereto, there being suitable connections between the side members 58 and 59 as indicated at 60 whereby a rigid tilttable frame is provided. 75

Journalized upon the lower portions of the arms 59 are sleeves 61 each having oppositely extending tongues 62 and 63. Fixedly attached to the tongues 63 by rivets 63' (see Fig. 4) are the flanges of bars 64 which 80 extend over the turn table 50 and some distance beyond the pivot rod 54 where these bars merge, along curved lines, into tines 65 constituting the middle members of the bottom of the shock former. To the outer 85 sides of these bars 64, at the fastened ends thereof are attached additional bars 66 which likewise merge along curved lines to tines which are substantially parallel with the tines 65 and which have been indicated 90 at 67. These tines 65 and 67 are so proportioned and positioned that, when the parts are in shock receiving position as illustrated for example in Figs. 1, 2 and 3 said tines will extend close to and upwardly 95 along the front face of the plate 28.

Pivotally connected to each of the tongues 62 is a lever, one of these levers being indicated at 68 and the other at 69. The lever 68 is formed of spaced bars connected together as shown particularly in Fig. 6, these bars extending along the upper and lower faces of the tongue 62. The lever 69, however, is formed in a single bar having a forked end 70 which straddles and is pivotally connected to the other tongue 62. The lever 69 extends between the bars of lever 68 and is pivotally connected thereto as indicated at 71 and arranged on the free ends of the two levers 68 and 69 are stop pins 70 100 105 to limit the swinging movement of the levers relative to each other in one direction. A pulley 73 is carried by the lever 69 close to its pivot 71.

Journaled upon the side members 58 so as 110 to rotate thereon are sleeves 74 having outstanding bearings 75. In these bearings are journaled upstanding shafts 76 limited in their rotation by stop pins 77 adapted to come against stop lugs 78 depending from 115 the bearings 75.

Extending toward each other from the shaft 76 are arms 79 pivotally and slidably engaged by links 80 which are pivotally attached to the outer ends of the levers 68 and 69 respectively. Additional arms 81 extend from the shafts 76 and carry pulleys 82. These arms 81 are preferably extended toward the levers 68 and 69. An elongated arm 83 is fixedly connected to one of the 120 125 130

shafts 76 and is also pivotally connected, as at 84, to another arm 85 slidably and pivotally mounted on the other shaft 76. This arm 85 has a slot 86 through which one of the shafts 76 extends as shown particularly in Fig. 4. Stop pins 87 are carried by the arms 83 and 85 and serve to limit the swinging movement of said arms in one direction. A pulley 88 is connected to one of the arms, 85, close to its pivot 84 and additional pulleys 89 are mounted on the bars 64 close to the tongues 63.

A transverse shaft 90 is journaled in the arms 59 above the sleeves 61 and loosely mounted on this shaft so as to rotate, is a drum 91. A ratchet wheel 92 is keyed or otherwise secured to the shaft 90 at one end of the drum 91 and a coiled spring 93 is arranged in the drum. One end of this spring 20 is attached to the shaft 90 while the other end is attached to the drum. A pawl 94 normally engages the ratchet wheel 92. Pivotally attached to the pawl 94 is one end of a rod 95. This rod extends between the intermediate bars 64 of the bottom of the shock former and is connected to a lever 96 which is pivotally attached, between its ends, to one of the tines 65, one end of this lever normally projecting outwardly beyond the tines 65 as shown particularly in Fig. 3.

Secured to the drum 91 and wound in opposite directions thereon are cables 97 and 98. The cable 97 extends partly around one of the pulleys 89 from drum 91 thence into engagement with the two pulleys 82, and the other pulley 89 and is attached, at one end, to one of the tongues 63. Thus when said cable 97 is wound upon the drum it will pull on the pulleys 82 and cause the shafts 79 to swing toward each other. The cable 98 extends from the drum 91 to the pulley 88 thence to pulley 73 from which it extends over a pulley 99 which is journaled on a rod 100 connecting the sides 58 of the tiltable frame and the shock former. From this pulley 99 the cable 98 extends downwardly under the pulley 57 and thence into engagement with pulley 55, under a pulley 101 on a standard 102 secured to the tiltable supporting frame 47 (see Fig. 3) thence upwardly to the drum 30 to which it is secured.

Fixedly connected to each of the shafts 76 are bars 103 forming a head to which are secured the central portions of bowed rods 104 constituting the sides of the shock former. When the shock former is in its normal or shock receiving position these rods lie in vertical planes and secured to the upper ends to certain of the rods are cables 105 which extend downwardly around pulleys 106 attached to the lower ends of said rods thence to springs 107 attached to the intermediate portions of the rods.

65 A spring 108 extends under the side mem-

bers 58 of the tiltable frame of the shock former and is attached at its ends to the lower ends of the shafts 76, thus tending to pull the upper ends of the shafts apart or away from each other when they are not held against such movement.

Mounted upon one side of the turn table 50 is a bracket 109 to which is pivotally connected a latch lever 110. One end of this lever normally extends over one of the side members 58 thus to hold the tiltable frame of the shock former normally in the position illustrated in Figs. 1, 2 and 3 and with the sides of the shock former extended upwardly. This lever 110 is located at that side of the turn table remote from the pulley 55 and connected to the same side of the turn table is one end of the cable 111 which extends within the groove 52 in flange 51 and thence laterally toward the binder, one end of the cable being secured to a heavy coiled spring 112 which is secured to the frame of the binder as shown for example in Fig. 1.

The tiltable supporting frame 47 of the machine is provided with a keeper 113 on one side thereof and which is normally engaged by a latch lever 114 pivotally connected to the frame member 1. A spring 115 serves to hold the latch lever normally in engagement with its keeper, thus to support the tiltable supporting frame in raised position. A releasing lever 116 is pivotally mounted, as at 117, upon the tiltable supporting frame 47 and is adapted, when thrust laterally, in one direction, to press against the latch 114 and disengage it from its keeper 113, thus to permit the tiltable supporting frame 47 to swing downwardly.

A stop 118 is arranged on the tiltable supporting frame 47 where it will be engaged by the latch lever 110 when the shock former is moved to delivering position, as shown in Fig. 7.

Pivotally mounted on the supporting frame 47 and adjacent the turn table is a lever 119 having a short arm 120 which extends toward the turn table so that when said turn table is moved to bring the shock former to bundle receiving position, the lever 119 will be actuated against the action of a spring 121. A cable 122 is connected to the long arm of this lever 119 and extends to the latch lever 42.

Attached to the lever 68 is one end of a rod 123. The other end of this rod is connected to the upper end of a lever 124 which is pivotally mounted on the rod 100 carrying the pulley 99. The lower end of this lever is adapted to rest upon the turn table 50 under normal conditions.

From the foregoing description it will be apparent that when the shock former is in bundle receiving position the tines 65 and 67 are extended vertically in front of the plates 130

28 and the side rods 104 of the shock former are disposed in vertical planes with their upper ends spread apart so that the cables 105 are extended downwardly along converging lines, as shown particularly in Fig. 9, this arrangement of the rods 104 being due to the fact that the shafts 76 are normally swung away from each other. Consequently as the apparatus herein described 10 travels alongside of the binder and the bundles are discharged from the binder, said bundles will be elevated as hereinbefore described and dropped into the space between the downwardly converging cables 15 105. These cables will be held normally taut by the springs 107 and will maintain the bundles parallel whether or not they completely fill the space between the rods 104. As the bundles pile up between the 20 cables 105 said cables will bend outwardly toward the rods 104. It is to be understood of course that as the lever 38 is freely mounted the spring 40 will shift the clutch member 37 into engagement with the clutch member 14 so that motion is normally transmitted from the pitman drive shaft through 25 chain 15 to the shaft 9 and the elevating chains thereon. The distance between the stop 41 and the clutch member 37 is greater than that from the stop 41 to the clutch member 36 and the spring 40 being stronger than the spring 39 it will be obvious that the 30 clutch members 37 and 14 will be normally in engagement with each other. The cable 35 98 is wound on the drum 80 and said drum is held against rotation by the pawl 32. With the cable 98 thus taken up, the toggle made up of the levers 68 and 69 is held extended with the tongues 62 pushed apart 40 and the tongues 63 pressed toward each other, thereby holding the bars 64 parallel or closed toward each other. The taut cable 98 also holds the toggle made up of arms 83 and 85 extended, thus to press the upper 45 ends of the shaft 76 apart to maintain the upper ends of the rods 104 spaced apart so that the opposed sets of rods 104 will be spaced equally thereby to allow the bundles to fall between said upper ends. Attention 50 is called to the fact that when the bundles are deposited in the shock former their butt ends will not engage the tines 65 and 67 but will, instead, engage the metal plate 28 and thus be free to spread without interference. 55 After a desired number of bundles have been deposited in the shock former in the manner described, the operator pulls upon the cable 46. This action causes the cable 45 and lever 43 to pull outwardly on the lever 60 38, causing said lever to move against the action of its springs 39 and 40 until the lower end of said lever is hooked into engagement with the latch lever 42. At the same time the pawl 32 is disengaged from 65 its ratchet wheel, thereby releasing the drum 30 and the cable 98. The release of the cable will result in the release of the arms 83 and 85 and, consequently, the upper ends of the shafts 76 will be allowed to swing toward each other for the purpose of compressing the shock. This shifting of the upper ends of the shafts 76 toward each other will be produced by the spring 93 which will promptly wind up the cable 97 on the drum 91, at the same time taking up slack in the cable 98. As the paid out cable 98 relieves the turn table of the restraining influence of said cable, it will be obvious that as soon as said cable begins to unwind from the drum 30, the spring 112, which is normally 70 under tension, will pull on cable 111 and cause said cable to unwind from the arcuate end of the turn table 50, thus causing said turn table to swing horizontally through approximately 180 degrees until stopped by the 75 latch lever 110 coming against the stop projection 118 as shown in Fig. 7.

As the shock is held under compression during this turning of the table 50, due to the pull of the cable 97 upon the pulleys 82 90 and the resultant binding of the rods 104 against opposed portions of the shock, it will be obvious that as the table is rotated the butt end of the shock will be moved away from the sheet metal plate 28 and pass the 95 flexible portion of said sheet.

After the shock former has thus been rotated the butt end of the shock, instead of resting on a metal plate 28 will come against the tines 65 and 67 and will be extended 100 rearwardly from the machine. When the latch lever 110 contacts with stop 118 upon the completion of the rotation of the turn table 50, the tiltable frame of the shock former will be released and the weight of the 105 butt end of the shock will cause the entire tiltable frame of the shock former to swing downwardly about the rod 54 as a pivot, bringing the tines 65 and 67 close to the ground. As the shock former begins to 110 swing downwardly in this manner the lever 124 which up till then has been held against movement by the table 50 and has consequently held the levers 68 and 69 locked, will be free to move with the result that the 115 sleeves 61 will be released and the tongues and bars 64 left free to swing apart for the purpose of spreading the butt end of the shock resting on them.

Simultaneously with the foregoing operation the links 80 will release the shafts 76 which will thus be free to rotate in their bearings, causing the lower rods 104 to shift outwardly from the shock. The tines 65 and 67 will also move apart as heretofore 125 described, thus to maintain the shock spread against the lower rods 104. Obviously this outward movement of the lower rods 104 is limited by the stop pins 77 and lugs 78. Likewise during this operation the spring 130

93, which is under tension, serves to keep a strong pull upon the cable 97 through the drum 91.

Just before the tines 65 and 67 reach their horizontal positions, the upwardly extending portions of the tines 65 strike the free end of the releasing lever 116 and cause said lever to push against latch 114 and disengage it from its keeper 113. Consequently the 10 tiltable supporting frame 47 will drop so that the tines 65 and 67 will thus be permitted to rest on the ground. However, before the tines touch the ground the projecting end of the lever 96 will strike the ground 15 and cause the cable 95 to pull on the pawl 94, thereby releasing the spring 93 and drum 91 so that the cable 97 will be relieved from the pull exerted by the spring. This will result in stopping the compressing and spreading 20 action of the apparatus and spring 108 will swing the shafts 76 apart, thus to spread the shock holder sufficiently to allow the free withdrawal thereof from the standing shock.

25 After the tines 65 and 67 have pulled out from under the standing shock the operator releases the held cable 46 and as the lower end of the lever 38 is held by the latch 42 it will be apparent that when this cable is 30 released the upper end of the lever 38 will move under the action of the spring 39 to bring the clutch member 36 into engagement with clutch member 35, thus causing the cable 98 to wind upon the drum 30. This 35 will result in resetting the levers 68 and 69 and the lever 81. It will also bring the tiltable frame of the shock former back to its normal position with its sides 58 resting on the turn table where it will be locked 40 by the latch 110. When the turn table is swung to its discharging position under the action of the cable 111, the cable 98 becomes seated in the groove 52 in flange 51 and, consequently, during the winding of the 45 cable 98 the turn table will be moved back to its initial position against the action of the spring 112 until the push or thrust of the turn table 50 against the end 120 of lever 119 is sufficient to overcome the spring 50 121. As soon as this spring is overcome the cable 122 will disengage the latch lever 42 from the lever 38 and allow said lever 38 to move bodily until it engages the stop 41 which will then act as a fulcrum and result 55 in disengaging the clutch member 36 from the clutch member 35. At the same time the other clutch members 14 and 37 will be placed in engagement with the result that rotation of the drum 30 will be stopped and actuation of the elevator will commence. It will be apparent that the amount of winding of the spring 93 will depend upon 60 the pull exerted by the spring 121.

Upon the completion of the operation

above described all of the parts are reset 6 and the formation of a shock can be repeated and the same deposited on the ground as described.

What is claimed is:—

1. A shocking machine including bundle 70 elevating means, a shock former for receiving bundles from the elevating means, and for holding said bundles upon their sides, mechanism for successively rotating the shock former and tilting it to deposit the 75 bundles on end, tines constituting the bottom of the shock former when said former is tilted to shock discharging position, said tines being extended upwardly when the former is in bundle receiving position, and 80 imperforate means extending between the butts of the bundles in the shock former and the upstanding tines for sliding engagement by said butts during the movement of the shock former to discharging position. 85

2. In a shocking machine a structure including an imperforate wall, a shock former having relatively movable sides, tines extending across one end of the shock former and adapted to extend upwardly in front 90 of the wall when the shock former is in bundle receiving position, means for depositing bundles on their sides within the shock former and with their butts toward the wall, and means for successively rotating and 95 tilting the shock former to move the butts of the bundles away from the wall and to deposit said bundles on end upon the tines.

3. In a shocking machine a revoluble and 100 tiltable shock former including side members, means for swinging the side members toward and from each other to open and close the shock former, means for rocking the side members to compress one end of a shock in the former and permit expansion 105 of the other end thereof, tines extending across one end of the shock former and adapted, when the former is tilted, to engage the butt ends of the shock and support the same, and means for moving said tines 110 apart during the spreading of the base of the shock.

4. In a shocking machine a structure having a solid front wall, a spring actuated turn table, power operated means for moving the turn table against the action of its spring and for holding the turn table in set position, a tiltable shock former supported by and movable with the turn table and including shock compressing sides and tines 115 extending across one end of the shock former, the said wall being extended between the tines and the sides of the shock former when the shock former is in set position, and means under the control of the operator 120 for releasing the turn table to shift it under the action of its spring out of set position, and means for automatically tilting the 125

shock former to bring its tines lowermost when the turn table has completed its rotation.

5. In a shock former a turn table, yielding means for actuating the same, means for holding the turn table against movement by its actuating means, a tiltable shock former connected to the turn table, means for holding the shock former against tilting movement relative to the table, means under the control of the operator for releasing the turn table from its holding means, and means for automatically releasing the tiltable shock former from the turn table upon the completion of the movement of the turn table by its actuating means.

6. In a shock former a turn table, yielding means for actuating the same, means for holding the turn table against movement by its actuating means, a tiltable shock former connected to the turn table, means for holding the shock former against tilting movement relative to the table, means under the control of the operator for releasing the turn table from its holding means, and means for automatically releasing the tiltable shock former from the turn table upon the completion of the movement of the turn table by its actuating means, and means operated by the tilting of the shock former for lowering the turn table toward the ground.

7. In a shock former a turn table, yielding means for actuating the same, means for holding the turn table against movement by its actuating means, a tiltable shock former connected to the turn table, means for holding the shock former against tilting movement relative to the table, means under the control of the operator for releasing the turn table from its holding means, and means for automatically releasing the tiltable shock former from the turn table upon the completion of the movement of the turn table by its actuating means, and means operated by the tilting of the shock former for opening said former to release the shock therein.

8. In a shocking machine a shock former including side members, arms extending at right angles therefrom, bars pivotally connected to the arms and extending above and beyond the side members and merging into tines extending at angles from the bars, supplemental tines connected to each of said bars, said tines constituting one end of the shock former, revoluble shafts extending at right angles from and adapted to swing about the side members, arcuate means connected to the shaft and constituting the sides of the shock former, means for swinging the shafts apart to open the sides to bundle receiving positions, and means for rotating the shaft to rock the sides thereby

to compress the top of a shock, and means 65 for swinging the tines apart to spread the bottom of the shock against the sides.

9. In a shocking machine a shock former including a tiltable frame, shafts extending at right angles from and adapted to 70 swing relative to the sides of the frame, each shaft being mounted for rotation, and side members fixedly connected to and movable with each shaft, and means for rotating the shaft to rock the side members, thereby 75 to compress the top of the shock and permit expansion of the butt thereof.

10. In a shocking machine a shock former including a tiltable structure, shafts extending at right angles from the sides thereof 80 and mounted for rotation, said shafts being adapted to swing toward and from each other, side members fixedly connected to and movable with the shaft, yielding means for swinging the shafts apart, power operated means for drawing the shafts toward each other to compress a shock, and power operated means for rotating the shafts to compress the top of a shock and permit expansion of the bottom thereof. 90

11. In a shocking machine a shock former including a tiltable structure, shafts extending at right angles from the sides thereof and mounted for rotation, said shafts being adapted to swing toward and from each 95 other, side members fixedly connected to and movable with the shaft, yielding means for swinging the shafts apart, power operated means for drawing the shafts toward each other to compress a shock, and power 100 operated means for rotating the shafts to compress the top of a shock and permit expansion of the bottom thereof, relatively movable tines constituting one end of the shock former, and means for moving the 105 tines from each other to spread the bottom of the shock during the compression of the top of the shock.

12. In a shocking machine a main structure for attachment to a binder, elevating 110 means carried by said structure, a tiltable supporting frame, a turn table mounted upon the free end portion of said frame, means for holding said supporting frame in elevated position, a tiltable shock former 115 mounted upon the turn table, and means operated by the tilting of the shock former for releasing the supporting frame.

13. In a shocking machine a main structure for attachment to a binder, elevating 120 mechanism carried thereby, a tiltable supporting frame, means for holding said supporting frame in elevated position, a turn table mounted upon the supporting frame, a shock former tiltably connected to the turn 125 table and movable to position to receive bundles from the elevating mechanism, a releasing lever movable against the frame

supporting means, said lever being extended into position for engagement and actuation by the shock former when tilted.

14. In a shocking machine a turn table, 5 a shock former carried by the turn table, elevating mechanism including a shaft, a drum shaft, a drum loosely mounted thereon, a coiled spring connection between said shaft and its drum, pawl and ratchet mechanism for holding the drum shaft against rotation, revoluble drive devices upon the two shafts, connected clutch members feathered upon the respective shafts, means under the control of the operator for shifting 10 the clutch members to couple the drum shaft to the drive mechanism, and to uncouple the elevator shaft and drive mechanism, means for locking the clutch members in shifted positions, means operated by the 15 actuated drum for rotating the turn table to bring the shock former to bundle receiving position, and means operated by the turn table when the shock former is brought to bundle receiving position, for releasing 20 the clutch members, and means for automatically shifting the released clutch members to couple the elevating shaft to the 25 drive mechanism and to uncouple the drum shaft from the drive mechanism.
15. In a shock former the combination with a turn table, of a tiltable frame connected to the turn table, shafts mounted to swing relative to the sides of said frame and being mounted for rotation, members fix- 30 edly connected to and movable with the shaft 35

and constituting the sides of a shock former, tines extending across one end of the shock former, means for moving said tines toward and from each other, a spring controlled winding drum, oppositely wound cables 40 thereon, means operated by the winding of one of the cables for rotating the shafts to shift the sides of the shock former and compress one end of a held shock, a power driven spring controlled drum, the other cable being connected to the last named drum and adapted, when wound thereon, to increase the tension of the spring in the first named drum and wind the first named cable, means operated by the winding of the 45 second cable by the power actuated drum for shifting the shafts toward each other to swing the sides of the shock former inwardly, and means under the control of the operator for releasing the power operated 50 drum from its drive means to permit unwinding of the cable therefrom and the winding of said cable upon the other drum under the action of the spring housing said drum thereby to permit movement of the 55 sides of the shock former away from each other.

In testimony that I claim the foregoing as my own, I have hereto affixed my signature in the presence of two witnesses.

INGOLF BIRKELAND.
